CLAIM

The ornamental design for a base for an I.V. pole, as shown and described.

DESCRIPTION

FIG. 1 is a perspective view of a base for an I.V. pole, showing my new design;

FIG. 2 is a top plan view of FIG. 1;

FIG. 3 is a bottom plan view of FIG. 1;

FIG. 4 is a left side elevational view of FIG. 1;

FIG. 5 is a right side elevational view of FIG. 1; and,
FIG. 6 is a perspective view of the base of FIG. 1 having one leg in a raised position.

The broken line showing in FIGS. 1 and 6 is for illustrative purposes only and forms no part of the claimed design.
